M. H. HARTZELL

FOLDING UMBRELLA

Filed Sept. 25, 1922

INVENTOR:
Morris H. Hartzell
BY:
Wiedersheim & Fairbanks
ATTORNEYS.

UNITED STATES PATENT OFFICE.

MORRIS H. HARTZELL, OF PHILADELPHIA, PENNSYLVANIA, ASSIGNOR TO SAMUEL S. FRETZ, SR., OF PHILADELPHIA, PENNSYLVANIA.

FOLDING UMBRELLA.

Application filed September 25, 1922. Serial No. 590,215.

To all whom it may concern:

Be it known that I, MORRIS H. HARTZELL, a citizen of the United States, residing in the city and county of Philadelphia, State of Pennsylvania, have invented a new and useful Folding Umbrella, of which the following is a specification.

My invention relates to a folding umbrella or parasol and it consists of novel joints for the folding sections of the ribs of the umbrella, and the attachments of the resilient means which retain the sections in normal condition.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figures 1 and 2 represent side elevations at a right angle to each other of portions of the sections of a rib, and the joint of said sections embodying my invention.

Figure 3 represents a side elevation of said sections and appurtenances in folded condition of said sections and also a side elevation of adjacent portions of the umbrella.

Figure 4 represents a perspective view of the members of the joint, shown detached from each other.

Figure 5 represents a longitudinal section of a portion on line 5—5 Figure 1.

Figure 6 represents a perspective view of a modification of one of the joint members.

Similar numerals of reference indicate corresponding parts in the figures.

Referring to the drawings.

1 and 2 represent sections of an umbrella rib. To the adjoining ends of said sections are secured the sleeves 3 and 4 respectively on each of which are the pairs of ears 5. The ears of the opposite sleeves are pivotally connected by the pin 6, thus forming the joint of the sections 1 and 2, admitting of said sections being folded for the purpose of a folding umbrella, and then admitting said sections to be unfolded forming continuities of each other producing a single rib as in an ordinary umbrella, when the umbrella may be opened and closed as usual. In order to retain the sections unfolded in their continuities I employ coil springs 7 which extend respectively along the sections, their

outer ends being connected with the clips 8 which are fitted on the sections and clamped firmly thereto. The inner ends of said springs are attached freely with the plate or piece 9 of metal or other suitable material, in openings 10 therein which plate is fitted within the opposite ears 5 and provided with the elongated slot 11 through which passes the shank of the pin 6, the latter thus connecting the plate with the ears 5, the springs being attached to said plate as above stated.

It will be seen that in the folding and unfolding of the sections of the ribs, the plate 9 is under the pressure of the springs 7, said pressure being exerted on the sections of the ribs as to hold them in distended or continuity-positions, the ears 5 moving freely on said plate and vice versa, thus guiding the ears in their motions, while also providing simple means for connecting the ears and strengthening the joint of the sections preventing twisting or torsion of the sections on each other at said joint.

In Figure 6 the plate is provided with the circular opening 12 to receive the pin 6, but the elongated slot 11 in the other figures is preferred as it imparts to the plate greater freedom of motion in the folding of the sections of the rib.

Attention is directed to the fact that the sections of the rib are not pierced and thereby weakened for the reception of the pivot pin 6, and that the plate 9 forms the bearings of said pin and the means for the attachment of the springs 3 to the sections of the ribs at their ends adjacent to the axial joint of said sections.

Having thus described my invention what I claim as new and desire to secure by Letters Patent is:—

2. In a folding umbrella, a rib formed of foldable sections with their adjacent ends overlapped, a single axial pin for connecting the latter, resilient means for holding said sections in normal condition, and a joint piece for said sections adapted to receive said pin for connecting said piece with the rib and to provide means for attachment of said resilient members.

2. In a folding umbrella, a rib formed of foldable sections with their adjacent ends overlapped, a joint for said sections, a single axial pin for connecting the latter, and resilient members for holding said sections in

unfolded condition, said joint including a piece adapted to receive said pin and provide means for the attachment of said members adjacent to said joint. a transverse elongated slot, and a single pin passed loosely through said slot and engaged in the overlapped ears of the sections. 10

- 5 3. In a folding umbrella, a rib composed of sections having adjacent ends formed with overlapping ears, and a member having openings for the attachment of springs and
